UNITED STATES PATENT OFFICE.

RAYMOND L. WHITMAN, OF HAMILTON, MASSACHUSETTS.

GOLF-HOLE RENOVATOR.

1,340,927.

Specification of Letters Patent.

Patented May 25, 1920.

Application filed October 3, 1919. Serial No. 328,226.

To all whom it may concern:

Be it known that I, RAYMOND L. WHITMAN, a citizen of the United States, residing at Hamilton, county of Essex, Commonwealth of Massachusetts, have invented certain new and useful Improvements in Golf-Hole Renovators, of which the following is a specification.

This invention relates to trimmers and particularly to a cutter for trimming or renovating holes such as the holes in a golf course.

Employing the golf hole as an illustration, it will be understood that such a hole having been once dug is liable to become misshapen or to be overgrown or otherwise rendered unfit for its purpose. This instance shows the strict requirement for uniformity and the necessity of having a clean cut, uniform and regular mouth.

For this purpose as well as for the variety of other uses to which it is or may be adapted, I have devised an implement simple and complete which is capable of rapidly and uniformly restoring the holes of a course or any other similar excavations which may need to be trimmed and standardized.

In the drawings which form a part of this application I have shown a form of device well adapted to the requirements of the example above indicated. Throughout the specification and drawings like reference characters are employed to indicate corresponding parts and in the drawings:

35 Figure I is a view of my device shown in working position.

Fig. II a sectional view of the same,

Fig. III a plan view and Fig. IV is a fragmentary section of the cutter.

40 In practice I preferably construct my device with a plate 1 having an opening 2. This opening when used for the holes of a golf course has a diameter of four and one-quarter inches to coincide with the standard hole of the course.

On the plate 1 I detachably mount a guide plate 3 having a central opening 4 axially aligned with the opening 2 of the plate 1 and slidably receiving the plunger 7. The 50 plate 3 is preferably detachably held by bolts 5 and wing nuts 6. Between the plate 3 and extending within the opening 2 is a female cutter member 10 shouldered at 12 and having a lower downwardly disposed cutting edge 10¹. On the end of the plunger 7 is a cutter disk 8 preferably shouldered at

8¹ to receive a cutting plate 11. This plate 11 has its upper edge 11¹ preferably spiraled or otherwise out of the horizontal plane so as to give a shearing effect when the cutter disk 8 is drawn past the cutting edge 10¹ of the female cutting member 10. The plate 1 is preferably roughened on each side as indicated at 1¹.

As illustrative of the manner of use of my 65 trimmer in the case of the renovation of golf holes, the keeper introduces the cutter disk 8 into the hole locating the plate 1 above the hole in such a way that the opening 4 in the plate is in general axial alignment with 70 that of the hole.

It will be noted here that these holes are fitted with a metal can or sleeve which preserves the hole and provides convenient means for emptying the hole in case it becomes partly filled.

75 The requirements of play, however, make it inadvisable to have this can extend entirely to the surface so that it in fact terminates a short distance below the level of 80 the ground so as to leave a natural mouth or ring of earth or turf.

In actual practice the turf tends rapidly to overgrow the mouth not only restricting the actual diameter of the hole, but considerably reducing its apparent diameter. This variation is a source of considerable annoyance to players in putting. It also introduces an element of variation from time to time in the course which materially effects 90 comparative scores and the basis of competition.

10 In addition to the overgrown tendency of the surrounding turf, holes become misshapen or distorted through variety of accidents and incidents. The utility of my present invention as applied to this problem lies in its peculiar efficiency in reforming the mouth of the hole with an exact and standard edge.

105 If the opening is merely overgrown by the turf, the cutter 8 having been introduced and the plate 1 located, the mouth may be shorn clean by an upward pull on the handle 9 which brings the upwardly disposed cutting edge 11¹ of the cutter 11 past the downwardly disposed cutting edge 10¹ of the female member 10 thus producing a clean shearing action all about the mouth of the hole.

110 In case a hole has become misshapen or distorted the cutter disk 8 is inserted usu-

ally by a slight tipping entry and the earth about the mouth of the hole then compacted by beating or stamping until it is laterally displaced so as to supply slight access of material all about the hole. The hole may then be trimmed as before described by drawing up on the handle 9 while holding the plate 1 firmly to the ground.

10 While I have dealt in some detail on this implement as applied to golf holes to which it is particularly adapted, there are a great variety of other purposes in which it may be conveniently used. I am not to be understood therefore as limiting my invention by reason of the foregoing illustrative explanation as its use and its modification and various parts and details may all be practised without departing from the spirit 15 of my invention if within the limits of the appended claims.

What I therefore claim and desire to secure by Letters Patent is:

1. A golf hole renovator comprising a plate having a sharp edged aperture there-through, a plunger adapted to pass through said aperture, a sharp edge cutter disk on the end of said plunger, said disk being of the size of said plate aperture, a detachable handle at the upper end of said plunger, a detachable guide on said plate adapted to support said plunger in central alinement with said plate aperture.

2. A golf hole renovator comprising a plate having a sharp edged aperture there-through, a plunger adapted to pass through said aperture, a cutter disk on said plunger, and a guide on said plate adapted to guide said plunger in central alinement with said plate aperture.

3. A golf hole renovator comprising a plate having a sharp edged aperture there-

through, a plunger adapted to pass through said aperture, a sharp edge cutter disk on said plunger of the size of said aperture, a 45 detachable guide on said plate adapted to support said plunger in central alinement with said cutting part.

4. A hole trimmer of the class described, comprising a ground plate having a sharp 50 edged aperture of the size of hole to be trimmed, a cutter of the size of said aperture and an operating handle for drawing up said cutter through said plate aperture.

5. A hole trimmer of the class described, comprising a ground plate having a sharp edged aperture of the size of the hole to be trimmed, a cutter disk having its upper edge disposed to coöperate with said aperture edge, said disk edge being out of parallel with the plane of the edge of the plate aperture.

6. In a golf hole trimmer, an apertured cutting plate having a downwardly faced 65 annular edge and a vertically movable cutter having an upwardly disposed peripheral edge disposed to be drawn up within said apertured plate.

7. In a golf hole trimmer, a cutting plate 70 having a downwardly faced cutting edge and a vertically movable cutter having an upwardly disposed cutting edge.

8. A method of reforming golf holes consisting in upwardly shearing the edge of 75 said hole against an opposed apertured plate.

In testimony whereof I affix my signature in presence of two witnesses.

RAYMOND L. WHITMAN.
